Winslow Brayley & Jeremiah Walker. Phillips, Haire.

Letter Patent

The Schedule referred to in these Letters Patent and making part of the same containing a description in the words of the said Winslow Brayley and Jeremiah Walker, themselves, of their improvement in a machine for rubbing off the hull from clover seed and also the hull of rice from the Kernel.

To all to whom these presents shall come. Be it known that the Winslow Brayley and Jeremiah Walker of Phillips in the County of Gloucester and State of Maine have invented a new and improved machine for rubbing off the hull from clover seed and also the hull of rice from the Kernel and that the following is a full and exact description of the construction and operation of said machine as invented and improved by us. The machine is thus constituted. Take two pieces of timber stiff and posts about four inches square each and five feet long. These are of hard wood and planed smooth. They are placed about ten inches apart and fast at this distance from each other by two square bars with strong binding through them. from one of these bars to the other there are two strong blocks of wood nailed or screwed to the bars about each end. Through these blocks of wood there is a hole and a pin inserted which turns a pinion gear for an iron lever. The inner end of which is made to a staple is the removable grater, hereafter to be described. This lever is the moving power of the machine, and as it has several holes through it at the end when it receives the pinion gear it may be given to it a greater or less purchase according to the strength employed in the operation. upon the outer sides of the posts and at right angles with them, are screwed on two boards about a foot wide each which gives it the form of a box. But to complete the box another flat piece of board is applied and is supported by guides in the centre which render it stationary. To the inside of this last piece of board are attached six grates, made of

Sheet iron with holes punched through it, so as to make them quite rough toward the upper end, then are also three triangular cleats which as well as the grates are placed transversely, and are made exactly to correspond with another set of grates, and cleats of similar size and shape soon to be described. The whole box is held together by wooden pipes and keeps upon the outside. The second set of grates to be described is attached to a piece of plank about five feet long, four inches thick and as wide as the box, or rather it is attached to a piece of board called a spring which covers the said plank. This plank being made smooth is placed inside the box contiguous to the posts, and being thus situated it is moved up and down by the help of the lever before mentioned, touching rolling four iron number inserted into the posts to prevent friction. Upon the spring nearest to the other side are six grates, made of sheet iron as those above described. They are about two inches wide and are made concave i.e. they are bent over slabs of wood which are in the form of stations of cylinders cut lengthwise, the grates are supported by the said slabs, placed opposite to each other at about three fourths of an inch apart are fastened to the spring of the plank by small nails. At the upper end of the spring are attached six cleats of wood concave on the outside with a smooth sheet iron on steel. These cleats are of a triangular shape and placed parallel to the grates and about as far apart as they are. The spring attached to the movable plank and containing the grates and cleats is thus described. On the first place the plank is made concave resembling the segment of a great circle. The diameter from the chord line to the circumference is about three quarters of an inch. The spring containing the grates etc is a flat piece of board about $3\frac{1}{4}$ inch thick fastened to the plank at each end and from the chord line to the curve of the plank. It is used thus, namely, when the machine is fed too plentifully, the spring has room by means of the elasticity of the plank to give way which prevents it from shaking and renders the operation more easy. When the machine is prepared for use, the posts stand a little inclined making an angle of about 40 degrees with a line drawn perpendicular to the plane of the horizon and are suspended in this position by two traces one on each side hatched to a pin going through
